UNITED STATES PATENT OFFICE.

ALFRED LOUIS SOHM AND CHESTER LOWELL ADAMS, OF LOS ANGELES, CALIFORNIA,
ASSIGNORS TO SOHM ELECTRIC SIGNAL & RECORDING COMPANY, OF SPOKANE,
WASHINGTON, A CORPORATION OF ARIZONA.

ELECTRIC RECORDING INSTRUMENT.

1,121,540.

Specification of Letters Patent.

Patented Dec. 15, 1914.

Application filed April 20, 1910. Serial No. 556,629.

To all whom it may concern:

Be it known that we, ALFRED L. SOHM and CHESTER L. ADAMS, citizens of the United States, and residents of Los Angeles, in the 5 county of Los Angeles and State of California, have invented certain new and useful Improvements in Electric Recording Instruments, of which the following is a specification.

10 Our invention pertains to apparatus for registering and recording numbers, characters and signs, or for the purpose of displaying any information signaled from mechanism connected up in circuit with the 15 same.

The object is to provide an apparatus of this character which has the capacity to record numbers of unlimited capacity, and it is specially designed for use as an employees' recording device, which has means for receiving and recording the number of a watchman's signal station or stations, and will print the year, month, day, hour, minute, as also record the forenoon as well as the 25 afternoon of the day, and in the cases of locks will also print the "in" or "out" signal and register the key used in locking or unlocking any door in the system, as well as note on the printed slip the position of the 30 "in" or "out" at the employee's entrance plate.

A further object is to provide a recorder which is electrically operated and also prints the operations of a plurality of numbering coils and timing devices of different apparatus used for diverse purposes, the signaling stations of which may be located at distant points, and to so arrange the mechanism that the different signals, although 40 given at substantially the same time will nevertheless by a selective system be taken up and recorded.

It still further provides a recorder with electrical coils to register numbers, letters, 45 figures and characters, words, like "In" and "Out", or other words, such as classified or secret codes, to have rolls to advance a printing ribbon, rolls to advance a paper web, a hammer to print, and a manually-wound 50 spring motor for the same, all of which will now be set forth in detail.

In the accompanying drawings, Figure 1 is a side elevation of the recorder with the side of the casing removed. Fig. 2 is a top

or plan view with the casing removed. Fig. 55 3 is a view of one end of the recorder showing the spring mechanism for operating the recorder. Fig. 4 is a view of the other end of the machine showing the operating spring and the printing hammer. Fig. 5 is a side 60 view showing the printing mechanism and the means for actuating the same. Fig. 6 is a detached view of a portion of the hammer, Fig. 7 is a diagrammatic view of the type bar printing mechanism, with the escape- 65 ment actuating mechanism for advancing the tape. Fig. 8 is a top view of the time printing device. Fig. 9 is a diagrammatic view of a portion of the frame showing detail of the operative mechanism and connection of the intermediate idler gear for moving the web. Fig. 10 is a view of the printed slip, and Fig. 11 is a diagrammatic view of the circuiting of the recorder. 70

In constructing our invention we provide a frame made up of a pair of vertical walls 10 11 to receive between them the printing and recording mechanism, held in alinement by suitable cross bars 12, and on the front 80 side is a casing, comprising a front wall 13, and secured by frame-holding pins 14, to receive within it the motor spring and mechanism connected therewith. In case we should use an electrical means for doing the printing this casing need not be used. On the rear side is a circularly-formed extension to hold the type bars and printing mechanism connected therewith. While, therefore, the wall 10 completely separates the mechanism 90 of the main frame from the spring motor mechanism in front of the wall 10, we have eliminated the wall 10 in the drawing, Fig. 1, for convenience in illustrating and pointing out the connections of the various 95 parts.

Centrally within the motor case is a shaft 14' on which is loosely mounted a drum 15 provided with a main drive gear 16. A hub 17 is fixed to the shaft 14' within the drum 100 to receive and hold one end of a coiled drive spring 18, the other end of the spring being secured to the peripheral wall of the drum. A ratchet wheel 19 is fixed to the shaft 14' and a pawl 20 hinged to the side wall 10, 105 and has a coacting spring 21, engaged with the ratchet wheel. The shaft or arbor 14' extends through the wall 10 of the case, as

at 22, so as to provide means for winding up the spring in the usual manner.

At the upper end of the frame and to the right of the spring motor driver is a shaft 23 on which is hung an escapement 24, the lower end of which has within two contact surfaces 25, 26, opposite each other and on a horizontal line with a cam shaft 27, parallel with the hanger shaft 23. This shaft 10 has a wheel 28 provided with four A-shaped cam faces 29, the angles of the A-shaped cams corresponding with the angles of the contact faces 25, 26, of the escapement. The contact faces are opposite to each other in 15 relation to the A-shaped cam faces 29, for purposes which will be explained hereinafter. A pinion 30 mounted on the shaft 27 is in engagement with the main driving gear 16.

20 The lower end of the escapement has a notch 31 so as to provide stop walls, and thus limit the oscillating movement of the escapement. Below this notch of the escapement, is a rock-shaft 31', which has 25 fixed thereto a rectangularly-formed body 32, in the upper side of which are two vertically-disposed pins 33 projecting out a sufficient distance to normally rest within the notch 31, and spaced apart in such a 30 manner that when one of the pins rests against its corresponding wall the other pin will be slightly beyond the other wall of the notch, as shown in Figs. 1 and 5. These pins are capable of a slight in and out movement, 35 being normally held up against the escapement by means of springs 34.

An arm 35, which passes through the rock-shaft 31', extends out a short distance where it is hinged to a vertical transmitting bar 40 36, Figs. 1 and 5, that extends down and has its lower end pivotally attached to a horizontal bar 37, the opposite end of which is hinged to a post 38.

The type bar magnet 39 has in close proximity to it a post 40, to the upper end of which is hinged a horizontal lever 41, provided with an armature 42 directly above the magnet 39, and a spring 41' secured to the post 40, and having its free end beneath 50 the bar 41, which serves to keep the armature normally away from the magnet 39. This lever 41, which is thus the armature bar, is for the purpose of operating the type bars, one of which is shown at 42', Fig. 5. This 55 type bar is hinged at 43, and has a type 44 at its free end, and its other end 45 is bent and hinged to a vertical link 46, the lower end of which is hinged to the armature bar 41.

60 The horizontal bar 37 which transmits motion from the escapement and the armature bar 41 are connected up by means of a vertical link 47, the upper end of which passes through the bar 37, and is adjustable 65 by a lock nut 48, and its lower end is hooked

to a common escapement bar 49 hinged to posts 50, and a bar 51 extending along below all the armature bars, of which 41 represents only one in the series, so that the action of the magnet in drawing down the 70 armature bar 41 will be to transmit a downward motion to the bar 37 and common escapement bar 49, and thus rock the shaft 31. The escapement lock-pin holder 32 being thereby oscillated or tilted, one of the pins 75 33 will be released from the end of the wall of the notch, and as the cam wheel is turned by the main drive gear counter clock wise, the inclined coacting surfaces between the contact 25 of the escapement and A-shaped 80 cam 29, will throw the escapement to the left until it is caught by the other pin 33 against the other wall of the gain 30. In like manner the return movement of the escapement to the right is performed by a 85 counter operation of the lock-pin holder. At the same time that the armature bar 41 moves downwardly the type bar 42' is also swung upwardly to print the character thereon. 90

As the main gear 16 of the spring motor is designed to actuate the paper feeding mechanism, and as the paper must be moved forwardly only a limited distance at each impulse of the magnet, or during each back 95 and forth swing of the escapement, we have provided a reducing gearing which affords a simple stop movement.

It should be observed that there is an armature bar 41 and a coil 39 for each of 100 the units digits, and that the action of the magnets, or any one of them, will print a units digit as well as actuate the escapement 24 through the underlying common escapement bar 51. Each of the tens digits 105 has also an armature bar and magnet similarly constructed, but each digit is printed by its corresponding type bar without affecting the escapement 24 since the tens digits have no bar similar to 51. 110

The paper web rollers 53, 54, are mounted on shafts 55, 56, journaled in the side walls 10, 11. The shaft 55 projects through the wall 10 and carries thereon loosely a small pinion 57 which meshes with the main drive gear 16, and is also connected with a larger intermediate idler gear 58 on the same shaft. A Maltese cross gear 59 is secured to the shaft 55 close to the wall 10, which engages with the concentric open flange 60 on the 115 side of the wheel 61, this latter wheel being mounted on a shaft 62, and has on one side, close to the Maltese gear 59, a projecting stud 62', this stud being slightly beyond the separated ends 63 of the flange 62, and 120 adapted to engage with the radial slots 64 of the Maltese gear 59. In action one of the incurved faces 65 of the Maltese gear, which are the same arc as the concentric flange 60, rests against the flange and thus prevent the 125 130

Maltese gear and the paper feed rollers 53 from turning, but when the stud 62 engages with one of the radial slots 64 one of the points of the Maltese gear enters the space 5 between the stud and end of the concentric flange, as at 63, thus imparting a rotary movement to the Maltese gear and feed roller a sufficient distance to move the paper forward one space. The intermediate 10 idler gear 58 also engages with a small pinion 66 mounted on the outer end of a short shaft 67, and to the inner end of the shaft is fixed a large pinion 68 engaging with pinion 69 on the end of a shaft 70 which carries the roller 71 of the printing ribbon 72. A similar pinion 73 is mounted on a shaft 74 which carries the lower ribbon roller 75. An intermediate gear 76 communicates motion from the gear 69 to gear 73. At the 20 other end of the case is a pair of rollers 77 78 mounted to correspond with the positions of the rollers 71 75, around which the ribbon operates, passing beneath the hammer of the printing mechanism and also above 25 the type bar mechanism, and above the time printing wheels. These latter rollers have an endless belt 79 around them provided with a spring 80 resting against the belt to place a drag on the wheels 77 and 78 so that 30 the top limb of the ribbon 72, passing toward the right, will be taut.

The upper paper feed roller 54 is mounted on the rear ends of links 82, the forward ends of which are hinged to a bracket 83 35 on the hammer frame 84 and to the wall 10.

The hammer frame 84 has a hammer vertically-movable within guides in the frame. This hammer bar 85 has a yoke 86 adapted to receive within it a four-pointed cam 87 40 mounted on a shaft 88, and this shaft extends past the main drive gear 16 and carries thereon a small pinion 89 by means of which the cam is actuated. Within the yoke, at its upper end, is a V-shaped cross bar 90 against which the teeth of the cam operate, and normally the bar 90 rides or rests on the upper tooth of the cam 87, so that as the latter turns it will be tripped, as shown by the detached Fig. 6.

50 The hammer bar has a pin 91 between which and the lower end of the frame is a coiled spring 92 which serves to give an impulse to the hammer bar when it is freed from the bar 90. The lower end of the hammer bar is clothed with leather bushing 93 as shown. The printing pad 94 which is directly below the hammer is hinged to a pair of horizontal arms 95, as shown in Figs. 1 and 5, and is, therefore, above the 55 paper slip 96 which is fed along by the rollers 53, 54.

Directly below the hammer we mount the printing device, which comprises the ordinary time clock wheels and operative mechanism, which are actuated by the magnet 60

97, and connected up with a master clock from the wire leads 98 99.

The printing wheels are mounted on a fixed shaft 100, on a line with the hammer pad 94, and this shaft has thereon printing 70 rollers or wheels adapted to print the month, 101, day, 102, hour 103, minute 104, a. m. and p. m. 105, year 106, and a special wheel 106' which may be used as a "late" designating wheel, or it may be used for any 75 other purpose. It is obvious that this series of wheels may be extended for other purposes not enumerated herein, to print other characters. Directly on a line with the pad and beyond the printing wheels described, 80 is a pivoted segment 108, having on its perimeter the designations "In" and "Out" 85 107 operated as will be hereinafter described, and a space 107' to receive the impressions from the type printing bars 42'. 85

The "in" and "out" segment 107 Fig. 1 is hinged on a fixed stud 108 so that when it is oscillated back and forth it will bring the words directly below the printing pad, and on a line with the printed characters of 90 the printing wheels. A spring 109 bearing against the segment serves to normally throw the segment over to indicate "in." The segment is connected by a link with an armature 111 of the magnet 112. The armature 111 is hinged at its lower end to the magnet frame and has a member which extends below the hinged point which is bent at approximately right angles and engages a spring 113 to normally keep it from 95 engaging with the magnet. 100

A lever 114 mounted in a post 115 on the frame 116 of the magnet, has a dog-catch 117 in engagement with the free end of the armature 111, and when so engaged the armature is in contact with the magnet 112. The other end of the lever 114 has an armature 118 directly above the vertical magnet 119. A spring 120, fixed to the post 115, and in contact with the dog-catch end of the 110 lever 114 serves to keep the lever in engagement with the armature 112, unless the coil 119 is energized.

It will thus be seen that the segment 108, being connected with the armature 111, and normally held so that the type "In" is in position for printing, represents the condition in which the apparatus is set for the working shift—that is during the periods from 8 to 12 and from 1 to 5. We also place in 115 the same train of printing wheels on the fixed shaft 100, Fig. 2, a wheel 106', which has the word "Late" as hereinbefore pointed out, which wheel is actuated by a magnet 127 connected up in circuit with a clock 120 having mechanism of such a character as to actuate the magnet and expose the "Late" character wheel during the predetermined period. This mechanism is shown in detail 125 in the copending application of Alfred L. 130

Sohm, Serial No. 581,793, filed September 13, 1910.

In order to more fully show the operation of the recording instrument we illustrate diagrammatically the circuiting of the system in Fig. 11, in which we show a differential-non-differential magnet 128, the end windings 129, 130, being wound non-differential, and the intermediate winding 131 being differential. 132 represents the battery.

The employees' entrance plate 133 has two columns of push buttons, one 134, representing the units digits, and the other 135 representing the tens digits, one side of each button being connected up through conductor 136 with one terminal of the intermediate differential winding 131 of the magnet 128, and the other terminal of this winding has a conductor 137 which connects with an intermediate tap 138 of the battery 132. The other side of the buttons of the units digits have conductors 139, each of which connects with one terminal of the magnets 39, the other terminals of the magnets being connected up by a common conductor 140 with one terminal of one positive winding 129, and the other terminal of this winding connects up with one pole of the battery 132 through wire 141. The conductor 140 also has a wire connection 142 with one terminal of the "In" controlling magnet 119, and wires 143, 144 from the other terminal of the magnet to the "In" button of the entrance plate 133.

The tens column of digits 135 have each a conductor 145 which connects with one terminal of the type printing magnets 39', and from each magnet is a connection to a common conductor 146, which connects with one terminal of the non-differential winding 129 of the magnet, the other terminal being connected by wire 147 with the battery 132. The common conductor 146 is also connected with one terminal of the "Out" controlling magnet 112, and this magnet is connected up with the "Out" push button 148, at the entrance plate, through wires 149, 150.

The watchman's plate, designated by 151, has a digits column which, in practice, has circuit closers or plugs, and the sockets for these plugs are connected up with suitable wires 152 with the tens side of the entrance plate 133, through wires 145, and by wires 153 with wires 129 which connect with the units digits column at the entrance plate.

A mistake button 154 has one side connected with the common conductor 136, the other side having a wire 155 which connects with one terminal of an operating magnet 156, and the other terminal of this magnet has a wire 157 connected up with one terminal of the non-differential winding 129.

The electrical clock referred to is con-

nected up in circuit with the battery through the wires 97, 98, and the electrical alarm and lock mechanism are connected up by means of a wire 150 which goes to the "Out" button of the entrance plate, wire 159, which connects with the "In" button of the entrance plate, and wire 160 which connects with one terminal of the differential winding 131.

The operation of the machine is as follows:—As the instrument is designed to record the impulses from a variety of mechanisms, such as terminals for employees' entrance plates, clock alarm, and watchman's circuits, and for locks, or other similar apparatus which it is desired to have connected up in a circuit and recorded at a central station, and to that end the recorder is provided with a plurality of recording wheels all mounted on the fixed shaft 100 or located in such a manner below the hammer that the characters will be printed on the paper web 96, and this paper is, when printed, adapted to be torn off where it emerges from the casing at 125, Fig. 1, and the slip will thus have recorded thereon, in successive order, the various impulses from the different instruments in the circuit, in the order of their time, giving the year, month, day, hour and minute, whether a. m. or p. m. and also an "In" and an "Out" designation, as well as a character, for instance, for a watchman, and also the record of locks, with the numbers and whether locked or unlocked, with the dates.

As this application has nothing to do with the structure of the clock which electrically operates the type printing wheels, it is not described herein.

The recording instrument being in the office and the transmitting button, for instance, at the employees' entrance, for registering the time of employees, the employee on entering will note the visual plate on the entrance plate. If the visual shows "In", and assuming his number to be 73, he will press the button 7, which is in the tens column of the plate, and then 3 of the units column.

The resultant action of the recorder is as follows:—When the signal 7 is sent the tens coil of the recorder is energized, thereby drawing down the character bar 41. As the tens coil 39 is connected only with the type bar 42', through the link 46, the figure 7 will be printed on the recorder slip and there is no further operation. The employee then presses button 3 of the units column and energizes coil 39 of the units set in the recorder, and as the armature bar 41 in this case is connected with both the type bar 42' through the link 46 and also with the escapement 24 through the bar 51, link 47, bar 37, link 36, and oscillating stop member 32, the section releases the stop pin 33 from the

notch 31. The cam-wheel 28 being driven counter-clockwise by the main driving gear 16 turns a quarter revolution, throwing the escapement to the right and is arrested by one of the teeth 29 at the inclined face 26. Thus an impulse is transmitted from the main gear 16 to the intermediate gear 57 and flanged-wheel 61, through the Maltese gear 59 to the paper roll-shaft 55, which moves the paper web forward the requisite distance. The cam-wheel receives its first impulse by the downward movement of the link 36 and when the actuating coil is de-energized the stop-member is again brought back to its original position so as again to swing the escapement to the left in the position shown in Fig. 1. During this operation the ribbon-rolls 69, 73, are also actuated through the intermediate gears 66, 68. The cam 87 of the hammer 85, being also geared up with the main drive gear 16, and the hammer being normally held up by the bar 90 which rests on one tooth of the cam, the action of the escapement turns the cam and the spring 92 drives down the hammer which is again restored by the next tooth of the cam.

It should be observed that the escapement being controlled by the pins 33 and operated by the bar 51, every time a units coil is energized, will be actuated so as to allow the transmitting pinion 57 and also the hammer cam-pinion 89 to make one-fourth of a revolution. Neither the paper nor the ribbon can move until the hammer returns to its normal position, as the common escapement bar 51, Fig. 5, must be returned to its normal position before the escapement will allow the stud 62', Fig. 1, to mesh with the Maltese gear, and as it requires only about $\frac{3}{2}$ of an inch movement in gear 89 to allow the hammer to be tripped, it takes $\frac{1}{16}$ of an inch movement of the stud 62' to move the Maltese gear. As both digits 7 and 3 have been printed, the mechanism is held until the other printing mechanism, namely the hammer, stamps the remaining portion of the line on the slip and returns to its normal position.

50 What we claim as new, is:—

1. An electric recording instrument, having mechanism therein for printing on a time slip, comprising a timing mechanism and printing wheels operatively connected therewith, and a type-bar printing mechanism the bars of which are radially-arranged and adapted to independently print an added portion to the end of the line stamped on said slip by the time-recording mechanism.

2. An electric recording instrument, having mechanism therein for printing on a slip, comprising a timing mechanism and printing wheels operatively connected therewith, and alined with said printing wheels

and adapted to be printed by the same stamping device, another type part and an independently operated type-bar printing mechanism having its own independent printing means, but with the print thereof alined with the print of the timing mechanism. 70

3. In an electric recording instrument, a timing mechanism having cooperating time-printing wheels, individual independently operated means for printing the number of the signaling station contiguous to the time print on the slip or web, a movable printing segment on line with the printing wheels and means set in operation by the operation 75 of said first named means for printing other information on the said slip.

4. In an electric recording instrument, a timing mechanism having printing wheels operatively connected therewith and adapted to print on the time slip, in combination with individual type bar printing mechanism, the bars of which carry signal number characters and are radially arranged to print said characters at a common point, 85 said bars being operatively connected with said timing mechanism but being capable of operating independently of each other, and means through the circuit from the signaling station to print the time and signal number and advance the time slip. 90

5. In an electric recording instrument, a timing mechanism having printing wheels operatively connected therewith and adapted to print on a time slip, a movable printing segment, individual means operatively independent of each other for printing the numbers of the signaling stations, and means through the circuit from the signaling outlet to print the time and signal number and advance said time slip; and means to indicate a mistake at the sending station. 100

6. In an electric recording instrument, a timing mechanism having a train of printing wheels operatively connected therewith and two sets of independently operative individual type-printing bars adapted to print on a line with the time printing wheels, one set of type printing bars being operated by a units set of digits switches, and the other 110 set of printing bars operated by the tens set of digit switches, said units set of printing bars being operatively connected with the printing mechanism of the time printing wheels. 115

7. In an electric recording instrument, a timing mechanism having a train of printing wheels operatively connected therewith and an "In" and "Out" character printing mechanism alined therewith, two sets of individual independently operated type printing bars adapted to print on the same line with the type printing wheels, one set of said type bars being operated by a units set of digits switches, and the other set of type- 125

130

- bars operated by a set of tens digits switches, said units set of type printing bars being operatively connected with the time-printing mechanism and with the paper feed roller 5 for advancing the paper.
8. In an electric recording instrument, a set of type-printing bars operatively connected with actuating magnets which are electrically in circuit with the push buttons 10 of a set of units digits, and a second set of type-printing bars similarly connected up with a set of tens digits, means whereby one of the tens digits may print on the recording slip in the tens place without changing 15 the position of the slip, and means for printing on the slip in the units place one of the units digits and thereby advancing the slip one position only during the operation.
9. In an electric recording instrument, a 20 timing mechanism and time printing wheels operatively connected therewith, a set of type printing bars adapted to print in alignment with the time printing wheels, and escapement and a spring motor to actuate 25 the same connected up with the type printing bars, a set of paper feed rolls and a hammer connected with said motor, and means whereby said motor will actuate the hammer and advance the paper through the 30 action of the type printing bars.

10. In an electric recording instrument, a timing mechanism operatively connected with a set of printing wheels, a signal number mechanism comprising a set of units and a set of tens terminal digits connected up 35 with corresponding type printing bars, and actuated by individual magnets in said recorder, a set of paper feed rolls, a printing ribbon, all controlled by the signal number mechanism.

11. In an electric recording instrument, a timing mechanism operatively connected with a set of printing wheels, a signal number mechanism, a set of units and a set of tens terminal digits connected up with corresponding type printing bars and actuating individual magnets in said recorder, an "In" and an "Out" character printing mechanism, a "Late" coil mechanism, a hammer for printing, a set of paper feed rolls, 45 and a printing ribbon all controlled by the signal number mechanism.

Signed at Los Angeles, in the county of Los Angeles, and State of California, this 6th day of April A. D. 1910.
